UNITED STATES PATENT OFFICE.

BONA ALLEN, JR., AND WILLIAM C. ALLEN, OF BUFORD, GEORGIA.

TANNING APPARATUS.

SPECIFICATION forming part of Letters Patent No. 716,358, dated December 23, 1902.

Application filed February 27, 1902. Serial No. 95,956. (No model.)

To all whom it may concern:

Be it known that we, BONA ALLEN, Jr., and WILLIAM C. ALLEN, citizens of the United States, residing at Buford, in the county of 5 Gwinnett and State of Georgia, have invented certain new and useful Improvements in Apparatus for Tanning; and we do hereby declare the following to be a full, clear, and exact description of the invention, such as will 10 enable others skilled in the art to which it appertains to make and use the same.

Our invention relates to improvements in apparatus for tanning hides, skins, and the like, and has for its object to provide a revolute tanning-wheel, certain features of novelty of which will hereinafter appear.

In order to more fully set forth our said invention, reference will be had to the accompanying drawings, wherein—

20 Figure 1 represents a transverse sectional view on the line 1 1, Fig. 2. Fig. 2 is a plan view of an apparatus for tanning constructed in accordance with our invention. Fig. 3 is a transverse sectional view on the line 3 3 of 25 Fig. 4, and Fig. 4 is a plan view of a modified form of our invention.

In the drawings, A represents the tanning-vat, adapted to be filled up to the water-line (indicated in Figs. 1 and 3) with tanning 30 liquor.

B represents a shaft mounted in bearings C C on the stationary standards D D, preferably located upon the outside of the vat. This shaft B runs longitudinally of the vat, 35 suitable packing or other means being provided at the points where said shaft passes through the sides of the vat to prevent leakage of the tanning liquor, which completely submerges the shaft.

40 E is a hollow drum rigidly mounted upon the shaft B, so as to rotate therewith. Into this drum E is placed the solid extract, access being had to the interior of this hollow drum through the door F, mounted upon the 45 hinges G G in the periphery H of said drum, the said hinged door being held closed by means of the cotter I, passed through the eye-bolts J and the lug J upon the door F. Perforations h h are provided in the periphery H 50 of this drum E, to allow the free entrance and exit of the tanning liquor to the solid extract for maintaining the strength of the liquor in

the vat. Upon the opposite end of the shaft B is rigidly mounted the cross-arm K, the arms of which extend out radially from the 55 shaft. These arms are perforated, so as to each receive a plurality of longitudinally-disposed bars L, said bars being in groups extending out radially from the shaft. The opposite ends of these bars L are preferably secured in perforations in the side of the drum E, such perforations corresponding with the 60 perforations in the cross-arms K; but, if preferred, a second cross-arm similar to the cross-arm K may be employed upon the opposite end of the shaft B, adjacent the drum E, for supporting the ends of the bars L. A pulley M is preferably mounted upon one end of the shaft B outside of the vat, by means of which power may be applied to rotate the 70 shaft.

Upon the radially-arranged bars L are hung the doubled hide or skin to be treated, any number of such hides being thus hung at one time. During the rotation of the shaft each 75 hide will assume a position similar to the hide N, (indicated in dotted lines in Fig. 1,) and so it will be seen that the hides being entirely submerged the action of the liquor will be uniform upon the same and the entire 80 surface of each hide will at all times be fully exposed to the action of the tanning or other liquor, the objectionable feature of the hideslapping upon each other being entirely eliminated.

85 In Figs. 3 and 4 we have shown a modified form of the apparatus in which we dispense entirely with the solid-extract drum H, a liquid extract or other tannin which would not have to be melted being used. In this construction we have also dispensed with the cross-arms K and have provided the two disks or drum-heads O, in which the hide-bars L are headed or otherwise secured, and instead of arranging the hide-bars in radially-disposed groups, as shown in Figs. 1 and 2, the bars of each group are arranged in a plane out of line with the shaft B. Although we have only shown this construction as applied to the modification illustrated in Figs. 3 and 90 4, it is obvious that in the apparatus shown in Figs. 1 and 2 the cross-arm K could be omitted and this latter arrangement of the hide-bars substituted. It is also obvious that 95 100

although we have only shown a single wheel in the vat we can and usually do construct a vat of sufficient dimensions and divided off into compartments to contain a series of tanning-wheels, each compartment containing tanning liquor of different strength, so that when a fresh pack of hides are put in they are first given the weakest liquor and then the next strongest, and so on until the pack is tanned. It is also obvious that many modifications might be made without departing from the spirit of our invention; but

What we claim, and desire to secure by Letters Patent of the United States, is—

1. In an apparatus for tanning, the combination with a vat, of a tanning-wheel, rotatably mounted in said vat, provided with a group of longitudinally-disposed hide-supporting bars, the bars of said group being arranged in a series extending inwardly from the periphery of the wheel, and means for rotating said wheel.

2. In an apparatus for tanning, the combination with a vat, of a tanning-wheel rotatably mounted in said vat, comprising end supports and groups of hide-supporting bars connecting said end supports, the bars of each group being arranged in series extending inwardly from the periphery of the wheel, and means for rotating said tanning-wheel.

3. In an apparatus for tanning, the combination with a vat, of a tanning-wheel rotatably mounted therein and provided with a group of longitudinally-disposed hide-supporting bars, the bars of said group being arranged in an alined series extending inwardly from the periphery of the wheel, and means for rotating said wheel.

4. In an apparatus for tanning, the combination with a vat, of a rotatable shaft passing through said vat, a hollow perforated drum carried by said shaft, a support carried by said shaft, and groups of hide-supporting bars carried by said support and running longitudinally of the shaft, and means for rotating said shaft.

5. In an apparatus for tanning, the combi-

nation with a vat, of a rotatable shaft passing through said vat, a hollow perforated drum carried by said shaft, a cross-arm upon said shaft, and groups of radially-arranged bars carried by said cross-arm.

6. In an apparatus for tanning, the combination with a vat; and stationary bearings adjacent the ends of said vat; of a rotatable shaft mounted in said bearings and passing longitudinally through said vat, a hollow perforated drum carried by said shaft, and hide-supporting bars carried by said shaft.

7. In an apparatus for tanning, the combination with a vat, of a shaft rotatably mounted therein, a cross-arm carried by said shaft, groups of hide-supporting bars carried by said cross-arm and disposed longitudinally of said shaft, the bars of each group being arranged in a series extending radially along the arms of said cross-arm, and means for rotating said shaft.

8. In an apparatus for tanning, the combination with a vat; of a rotatable shaft passing longitudinally through said vat, a hollow drum mounted upon said shaft, provided with a plurality of perforations in its periphery, a hinged door in said drum, and means carried by said shaft for supporting the hides.

9. In an apparatus for tanning, the combination with a vat; of a longitudinally-disposed shaft passing through said vat, a hollow drum provided with a plurality of perforations in its periphery, mounted upon said shaft, a hinged door communicating with the interior of said drum, a cross-arm carried upon the opposite end of said shaft, and hide-supporting bars arranged in radial groups, supported in openings in said cross-arms and drum.

In testimony whereof we affix our signatures in presence of two witnesses.

BONA ALLEN, JR.
WILLIAM C. ALLEN.
